UNITED STATES PATENT OFFICE.

EDWARD H. COVEL, OF NEW YORK, N. Y.

IMPROVEMENT IN GENERATING ILLUMINATING-GAS.

Specification forming part of Letters Patent No. 172,707, dated January 25, 1876; application filed January 7, 1876.

To all whom it may concern:

Be it known that I, EDWARD H. COVEL, of the city of New York, in the county of New York and State of New York, have invented certain new and useful Improvements in Process and Apparatus for Generating Illuminating-Gases; and I do hereby declare that the following is a full, clear, and exact description thereof, which will enable others skilled in the art to which it appertains to make and use the same, reference being had to the accompanying drawings, and to the letters of reference marked thereon, which form a part of this specification.

This apparatus is composed, essentially, of two parts, viz: first, one or more cupolas for the generation of hydrogen; and, second, a carbureting apparatus, by which a uniform carbonization, to any desired candle-power, of the hydrogen gas is effected.

It is necessary that I should describe each of these apparatuses and their associate devices in detail, as their construction and effects are somewhat peculiar.

In the drawings, Figure 1 is a vertical section of the cupolas, and an end view of the carbureter. Fig. 2 is an elevation of the apparatus, partially in section. Fig. 3 is a transverse vertical section of the carbureter. Fig. 4 shows an elevation of the cupola, cooler, and carbureter, and a vertical section of the auxiliary test-chamber. Fig. 5 is a modification of the auxiliary test-chamber.

In the manufacture of hydrogen and other gases by the decomposition of either wet or superheated steam, by being forced into contact with highly-heated coke, a matter of the first importance is to maintain the temperature of the coke to a decomposing-point.

This condition must be effectually secured in order to separate the well-known elements (hydrogen and oxygen) composing the heated water or steam—the hydrogen being set free, and the oxygen combined with carbon of the coke to form carbonic oxide, both important basic constituents of illuminating-gas.

It is found that steam, however highly heated, practically will always be of a lower temperature than the incandescent coke, and

the tendency of the steam, when forced in, upon, and among the lumps of heated coke, is to reduce the temperature of the heated coke to the temperature of the steam, which is always below the decomposing-point, and thereby endangers the effectual separation of the elements of water. This I believe to be a feature of controlling importance in the manufacture of hydrogen from water for illuminating or heating purposes.

I shall now proceed to describe the apparatus I employ in carrying out this part of my invention.

Fig. 1, A is the cupola-furnace, in which the steam, superheated or otherwise, is to be decomposed. This furnace is constructed of fire-brick, cased with iron, or common brick, and forming a deep cylindrical space for the reception of coke, coal, or any other suitable substance.

At the bottom of the furnace is an opening, A², similar to the opening of a common gas-retort, provided with a substantial and close-fitting door. The object of this opening is to gain access to the interior of the furnace for the purpose of igniting the coke, and also for clearing out the furnace when required. This opening, when the coke is well lighted, is kept closed (air-tight) by a door, until the coke in the furnace is exhausted and a new charge is required.

C¹ is an opening made in the side of the furnace, near the bottom, to admit heated air into the furnace and upon the coke, its object being to keep up the combustion of the coke and restore heat to it when lost by the too constant use of steam. The air is supplied to the furnace by a common tight positive blower, located at any convenient point, and kept in motion, when required, by any of the well-known means. This air may be heated by passing it from the blower through a heated pipe or other medium, or may be delivered into the furnace through the opening or tuyere C¹ at an ordinary temperature. If there is any difference whether the air be heated or not, it is found to be in favor of heated air, which may be heated by forcing it through a coil of heated pipe or conduits, through a

heated chamber filled with broken fire-brick, or by any of the well-known devices for heating air.

Near the bottom of the furnace, and opposite the tuyere C¹, is another opening or tuyere, C², for superheated steam. The steam is obtained from a boiler located in any desirable place, and heated wholly or in part by the heated gases, (carbonic oxide, &c.,) conducted from the furnace at C³ to a proper burner, which serves to heat the boiler; or the boiler may be heated simply by the hot products of combustion escaping from the furnace.

When the coke in the furnace is well ignited, and the cupola has reached a high decomposing temperature, the supply of air is cut off by closing cock C¹, and is replaced by superheated steam, which enters through the tuyere C². The steam, coming in contact with the highly-heated coke, is transformed into a mixture of hydrogen and carbonic oxide, which gases, when properly charged with the vapor of a fluid hydrocarbon and subsequently subjected to the high temperature of a heated retort and lime purification, becomes a permanent or fixed illuminating-gas, and is gathered into gasometers by well-known means.

As the admission of the superheated steam into the furnace causes the rapid cooling of the cupola, it is soon suspended; then air is again introduced to thoroughly ignite the mass of coke, and bring it again to its proper high temperature, in order that the operation may be renewed, and so on, alternating air and steam indefinitely.

It will now be seen that the action of the apparatus must necessarily be intermittent. I therefore avail myself of the use of one or more of these furnaces or cupolas, according to the amount of gas required to be produced in a given time; and while one furnace is decomposing steam and generating gas, the other will be getting up its heat, and vice versa, by which means a constant supply of gas will be given off from the apparatus. When but one is used, however, gas is being generated the greater portion of the time. It will also be seen that when cock C¹ is opened to admit air into the cupola, cock C³ must be opened at the same time, to discharge the products of combustion to the boiler or into the open air.

When steam is to be admitted to the cupola A, cock C² must be opened, and, at the same time, cock C⁴ must be opened, in order to discharge the hydrogen and carbonic oxide from the cupola into the cooler Y, or into the carbureter and mixer, and thence to the retorts. This I regard as the first step in my process. The second I will now proceed to describe.

In Fig. 2, A is the cupola. B is the carbureter. G is the exhauster and mixer. N is a bench of retorts. O is the air-blower, and P is the boiler.

In the manufacture of this gas, known as

"water-gas," as above set forth, I have said I regard the above simple and effective means I employ for this purpose as very important, and well adapted to the rapid and cheap manufacture of hydrogen, as being by far the largest portion of gas composing the gaseous illuminants now in use.

But there is still another feature or step in the process of this invention, equal in importance to the above-described step, that must receive serious attention where a uniform gas of a specified candle-power is desirable.

It is well known that all gaseous bodies employed in the manufacture of illuminating-gas receive their luminosity from the carbon contained therein. Hence it is very desirable that said gaseous bodies should receive their necessary carbon in a uniform and regulated manner, and that, too, at the option of the operator. This is that other element or step referred to in my process above, which I shall now proceed to describe.

The first thing to be done after the gas has been generated in the cupola and is being discharged therefrom is to reduce its temperature, for it must be obvious that the gas is too hot when it leaves the cupola to receive the carbon vapor in a regular and uniform manner. The operator could not control the amount of carbon vapor to be added to the gas. It is, therefore, desirable that the heat in the fresh gas should be reduced in temperature, and that can easily be done in any ordinary gas-works by passing the gas from the cupola through a set of condensing-pipes, Y, or any other mode of cooling down the gas may be employed, and in very cold weather, and under some circumstances, this may be omitted.

The gas having thus been prepared to receive the naphtha or other hydrocarbon vapor, it is admitted to the carbureter B. Here it is important that the carbon vapor should be added, at the will of the operator, to the cool hydrogen in fixed and definite quantities or proportions, and of about the same uniform specific gravity, in order to prevent that stratification of the gas, when it arrives in the holder, found so objectionable in the use of naphtha in gas-making. This previous formidable difficulty is entirely obviated by this process, and by the following device, (see Fig. 2:)

Letter B is an apparatus in which the light and heavy fluid hydrocarbons are used simultaneously by rotating at intervals the chamber in which they are contained, thereby causing a uniform carbonization, or nearly so, of the gas or air passing the apparatus, and utilizing all the hydrocarbon fluid contained therein. The gas or air, after leaving the rotary chamber, passes to the mixer G, where it is rendered uniform as to the photometric condition of the gas, and thence to the heated retort. This mixer G acts as an exhauster,

and as its action is quite well understood by persons skilled in gas-making, I will simply say that the pressure in the heated retorts and in the revolving carbureter are both regulated and controlled by increasing or diminishing the speed of the exhauster and mixer.

The degree of carbonization may be regulated, at the will of the operator, by means of an adjustable valve, which, in its different positions, will cause the whole, or only a part, of the gas passing through the machine to pass through the volatile liquid in the rotating carbonizing-chamber.

Rotating carbureter B is a cylindrical vessel, built of sheet metal, except possibly its ends, which may be of cast-iron. On each of its ends, and concentric with the cylinder, is a hollow trunnion, B¹, which rests on the timbering or other fixed supports B². One or more levers, or a belt and pulley, H, are secured to either or both ends of the cylinder, for the purpose of turning it over a half-revolution on its trunnions.

The vessel B is built of two half-cylinders, each having an externally-projecting flange, a, by means of which the two semi-cylinders are bolted together. Screw-bolts should be used for this purpose, as it may be necessary to take the vessel apart at intervals for the purpose of clearing or repairs. The joint made by the two half-cylinders should be very tight to prevent leakage. Between these two flanges a, as above described, there may be introduced the edges of the diaphragm B³, which divides the chamber into two equal, or nearly equal, compartments. The bolt which holds the two flanges a together will also pass through the diaphragm, and hold it in position. The diaphragm B³ is divided into two parts in the center of the vessel, so as to form a small cylinder concentric with the vessel B, and through the center of the cylinder thus formed the regulating gas-pipe X will be placed, so as to leave an annular opening between the pipe and the cylindrical part of the diaphragm, as shown in Figs. 2 and 3.

The ends of the gas-pipe X are joined with the ends or heads of the cylinder, and open ports x in the sides of the said pipe, just inside of the front head a¹, permit the incoming gas to pass into the chamber B, as required, and the gas so passed into the carbureting-chamber returns to the pipe X again through the open ports x', which are located at the other end of the chamber B, just inside of the head a². The diaphragm b³ is to be finely perforated throughout its entire extent within the chamber b, both in its flat and in its cylindrical parts. The induction gas-pipe D is connected with the hollow trunnion on the front end of the cylinder B by means of the stuffing-box a³, and the connecting gas-pipe D' is attached to the other end of the rotary carbonizer by the stuffing-box a⁴. By this arrangement the gas to be carbonized may be conducted into and

out of the rotary carbonizer without leakage, and the chamber B at the same time be left free to turn on its axis, whether the chamber B is allowed to make a complete rotation around its axis, or only a semi-rotation; or rocking motion is entirely immaterial, and will depend upon the arrangement of the lever H, which may permit a whole rotation or not. At the front end of the apparatus is a valve, X¹, which is arranged to close the front end of the pipe X, on which the said valve is seated, as shown in Fig. 2. This valve may be opened or closed, or adjusted to suit, by means of the valve-rod X² and the operating-wheel X³, which wheel is in an accessible position outside of the apparatus. The rod X² passes through a stuffing-box, a, on the induction-pipe D, and inside of the said pipe it is threaded, so as to engage the nut X⁴, which is fixed inside of the said pipe, or to the hollow trunnion on that end of the apparatus. Just inside of the two heads of the chamber B are placed two diaphragms, a⁵, which close down tightly to the pipe X, and also to the cylindrical sides of B, except in the small port-spaces a⁶. (Shown in Fig. 2.) The spaces between the diaphragms a⁵ and the ends of the chamber B are sufficiently large to accommodate the flow of gas through the apparatus, and are in open communication with the ports x and x' of the pipe X.

Within each of the compartments of B is placed a frame-work, E, as shown in Figs. 2 and 3, and between the ribs of this frame-work are stretched wires or strips of felt, or any other suitable porous substance, for the purpose of extending the evaporating-surface, as represented by E' in Figs. 2 and 3. The object of these obstructions will further appear in the description of the process.

The connecting-pipe D' connects the cylinder B with an ordinary rotary mixer or positive blower, G, Fig. 2, in the nature of an exhauster, the motion of which, either faster or slower, will regulate the motion of the gas and control its pressure. A McKenzil blower will answer all purposes, and, being well known, need not be further explained.

In the apparatus constructed as above described, the process of this part of my invention is as follows: A sufficient quantity of naphtha or other hydrocarbon fluid (the quantity varying, of course, with the size of the apparatus, but usually several barrels) will be put in the chamber B through its opening a⁶, and the fluid so introduced will pass through the perforations of the diaphragm in the direction of the arrows k, and will fall into the lower half-cylinder B in a fine shower, this operation being continued until all of the fluid shall have passed below the diaphragm, and then the cylinder will be given a half-revolution by means of the lever H, when the fluid will again pass through the diaphragm, as before, and so on. The operation of turning the

cylinder will be repeated throughout the process until the fluid hydrocarbon placed in the cylinder shall all have been used up without any waste or residuum. After the gas has passed the carbureter B it enters the auxiliary chamber and the mixer G, where it becomes thoroughly mixed with the vapor of naphtha or other suitable fluid hydrocarbon, and from thence it is forced to the heated retort, where, by the action of the heat, it becomes fixed and permanent.

In order to properly regulate the quantity of carbonization of the gas, I introduce the gas-equalizing pipe X, which will, on the opening of the valve X¹, admit the uncarbureted gas in a current, (represented by the arrows g'). This uncarbureted current g' will mingle with the carbureted current g in the pipe D' or the chamber F, or the mixer, as may be the most desirable, the object being to thoroughly mix and determine the photometric value of the gas before it enters the heated retort.

This I regard as a feature of much importance at this stage of the process. It will be seen, therefore, if the gas, uncarbureted, is forced to mingle with the carbureted gas, either in the chamber F or the rotary mixer, or both, that the different gases will readily combine, and may easily be rendered of a uniform quality, and of any photometric standard required, by simply adjusting the valve X¹, as may be desired, from time to time.

The auxiliary chamber F, whether placed before or after the rotary mixer, will be employed to receive the mechanically-mixed gas before it enters the heated retort, where the candle-power of the mixture can be determined by the use of the pipe M, having cock m' and regulated burner m.

When the apparatus is in action, and the gas is under a certain amount of pressure, the burner m may be kept lighted, so that the operator may proximately determine at once and at all times its candle-power; or a photometer may be employed for greater accuracy for that purpose, or both may be found convenient and useful.

The known and desirable candle-power of the gas can by this means be determined before it enters the heated retort, its homogeneous character be secured, and all stratification of the gas (found so objectionable in other processes) will be effectually obviated, while the heated retort will be kept free from all unconsumed carbon by having the gas thus prepared and stripped of all supersaturation, thereby admitting nothing but clean gas and vapor into the retort. This gas will be conducted from the heated retort to the lime purifiers, in order to remove from it any stray sulphur which may arise from the use of coal or coke in the cupola, or any carbonic acid that may be present.

I do not limit myself to the precise details

of the apparatus herein described, as it is evident that apparatuses of the nature specified may be combined in an analogous manner to effect the same result.

The auxiliary test-chamber may be constructed, as shown in Fig. 5, with a flexible top or drum working in a water-seal, whereby it will accommodate different measures of gas and regulate its pressure.

The retorts for fixing the gas are filled with fire-brick, or other refractory material, for presenting an extended heating-surface and keeping the gas longer in contact with such surface.

The steam may be superheated by passing it through coils of clay pipe located in a furnace, or through a chamber filled with fire-brick and located in a furnace, or by other means.

All the different parts of the apparatus are connected by the proper pipes and couplings, and are provided with cocks and plugs where necessary.

Having thus described my invention, what I claim, and desire to secure by Letters Patent, is—

1. The process of manufacturing illuminating-gas, which consists in producing water-gas by passing alternate currents of air and steam through a body of incandescent carbon, cooling such gas, and then carbureting it by passing it at a regulated flow through a constant shower of liquid hydrocarbon, substantially as set forth.

2. The process of manufacturing a permanent illuminating-gas of a definite photometric value, which consists in generating non-illuminating gas by decomposing steam by passing it through incandescent carbon, cooling such gas, enriching it with a definite and regulated percentage of hydrocarbon vapor, mixing the gases and vapor uniformly together, and then fixing the mixture in a heated retort, as set forth.

3. The primary generator A, cooler Y, and carbureter B, constructed as described, in combination with a test-chamber, F, exhauster and mixer G, substantially as and for the purpose described.

4. The primary generator A, cooler Y, carbureter B, test-chamber F, and exhauster and mixer G, in combination with one or more retorts, N, substantially as and for the purpose described.

5. The combination of a rotary carbureter, an adjusting pressure-regulating chamber, provided with a test-burner or photometer, a rotary exhauster and mixer, and one or more heated retorts, as set forth.

In testimony that I claim the foregoing as my own I affix my signature in presence of two witnesses.
